UNITED STATES PATENT OFFICE.

JOHN ELLIS, OF PITTSBURGH, PENNSYLVANIA, ASSIGNOR TO BELER WATER HEATER COMPANY, OF PITTSBURGH, PENNSYLVANIA, A CORPORATION OF PENNSYLVANIA.

THERMOSTATIC GAS-VALVE-OPERATING MECHANISM.

1,093,771.

Specification of Letters Patent. Patented Apr. 21, 1914.

Application filed April 25, 1913. Serial No. 763,566.

To all whom it may concern:

Be it known that I, JOHN ELLIS, a citizen of the United States, residing at Pittsburgh, in the county of Allegheny and State of Pennsylvania, have invented a certain new and useful Improvement in Thermostatic Gas-Valve-Operating Mechanism, of which the following is a specification.

My invention relates to thermostatic-gas-valve controlling mechanism of the class employed in automatic heaters, principally for domestic purposes, relating more particularly to the class in which hot water is maintained in storage and supplied therefrom at a given temperature.

The invention has for its object, to bring about a quick action of the fuel supply valve so that the full volume of gas may be supplied to the burner, practically instantaneously, rather than gradually supplied thereto, thus effecting a more rapid heating of the water to the desired temperature and more economical use of fuel, as well as preventing the usual or frequent-occurring "back-flash" of gas into the mixer of the burner when the gas is first fed to the burner at a very low volume and gradually increased, particularly when the fuel gas employed is that known as "artificial."

Broadly, the invention consists in interposing between the thermostat and gas valve, yieldable means, adapted when the temperature of the water falls below a predetermined degree, to suddenly unseat the gas valve to permit, practically, the full volume of gas being at once supplied to the burner.

The present invention is capable of being embodied in numerous structures for automatically opening the gas valve thermostatically, the general features of construction and operation of that here shown, to which the improvement is applied, being similar in many respects to that shown in U. S. Patent No. 1,049,829, granted to me January 13th, 1913, for gas controlling mechanism for water heaters.

In the accompanying drawings: Figure 1 is a side elevation of the mechanism, partly in section. Fig. 2 is a plan of a portion thereof. Fig. 3 is a side elevation of that shown in Fig. 2. Fig. 4 is a side elevation of a detail portion of the mechanism, partly in section. Fig. 5 is a side elevation of a storage system, showing the application of the mechanism thereto.

The structure illustrated, comprises a

chamber formed of the two connected sections 1 and 2, included in the gas supply line 3. The upper section 1 of said chamber, communicates with the lower section by way of an opening 4 formed through the partition 5 therebetween, which opening is controlled by a disk valve 6 having a downwardly extended stem 7 and guides 8 formed upon the under side thereof, and a short stem 9 upon the upper side and projects into an opening 9' in the cap 10, a spiral spring 11 being arranged in said opening to engage the stem of and insure seating of the valve when necessary. The lower section 2 of said chamber, is provided at its rear with a large screw 12 and a small screw 13, and at its forward portion with a boss into which is threadably connected a thermostat tube 14 having a rod 15 of porcelain, or other material of very low expansive and contractive qualities, fixed at the forward end 14' thereof and projecting at its free end into the chamber.

Within the chamber section 2, is loosely arranged a support 16 having two pairs of lugs 17 and 18, respectively, formed thereon, said support engaging and adapted to be adjusted in a direction toward the thermostat rod by the said screws 12 and 13. This support has pivotally secured thereto, between its lugs 18, a primary lever 19, which lever is also pivotally connected to the end of a thrust pin 20 engaged at its opposite flanged end 20' by the thermostat rod, and has further connected thereto, between its lugs 17, a secondary lever 21 in engagement with the primary lever and adapted to communicate motion to the gas valve. In this instance, the improvement is applied to the secondary lever, and consists in forming said lever with a boss 22 at its free end within which is arranged a spiral spring 23 and a tension adjusting screw 24. Pivotally secured at one of its ends upon this secondary lever is a member 25, the free end of which is engaged at its upper side by the stem 7 of the valve and at its under side by the spiral spring 23, a set-screw 26 passing through said pivoted member into the secondary lever for the purpose of adjusting the distance of depression between them.

In Fig. 5 the above described gas-valve controlling mechanism is shown connected up to the burner of a suitable heater 27, by the gas line 3, and in the return circulation connections 28 of a suitable boiler or storage

tank 29, for the purpose of illustrating one of its several applications to heaters.

In practice, the spring 23 is adjusted, by the screw 24, to such tension that at the instant the pivoted member is depressed to a predetermined distance, as for instance to almost parallel relation with the secondary lever, that the gas pressure acting upon the upper surface of the gas valve, when said valve is fully seated, and that of the spring 11, will be sufficient to overcome said pressure.

Briefly, the operation is as follows: The gas being turned on at the cock 30, and ignited at the burner by the usual pilot light, the tube 14 extending into the circulation line 28, becomes gradually heated from the rising temperature of the water, drawing the rod 15 therewith, thus reducing the pressure exerted thereby upon the pin 20 and levers 19 and 21, respectively, said lever 21 descending and permitting the gas valve to be seated and cut off the supply of gas to the burner. As soon as the water falls below a predetermined temperature the thermostat tube begins to contract, gradually forcing the rod 15 toward the chamber and exerting pressure upon the pin 20, which pressure is communicated to the primary and secondary levers 19 and 21, causing the latter lever to be elevated and, ordinarily, raise the gas valve gradually from its seat to again supply gas to the burner to reheat the water to the desired temperature.

With the present improvement, instead of the gas valve being gradually raised from its seat, as the tube 14 contracts, the pivoted member 25 of the secondary lever will be depressed as said secondary lever is elevated until both the pivoted member and lever meet at that point, at which time the tension of the spring 23 will have overcome the pressure of the gas exerted upon the valve, resulting in the sudden expansion of the spring 23 and elevation of the valve, thus permitting the full volume of gas to be supplied to the burner of the heater and thereby quickly restore the water to the desired temperature. As the thermostat tube expands and the valve descends to a point close to its seat, the accumulating gas pressure in the chamber overcomes the then slight pres-

sure of the pivoted member on the valve and closes said valve suddenly, thus cutting off the supply of gas to the burner.

I have shown and described the improvement in connection with the secondary lever of one particular mechanical construction for opening the gas valve by the action of a thermostat, and as the lever is capable of being changed in form, and as the location and application of the improvement may also be changed in such mechanisms, I do not wish to limit myself to what is here shown and described and therefore consider such changes to be within the limits of the following claims.

What I claim is:

1. The combination of a thermostat, a lever operated thereby, a valve, a member engaging said valve and pivotally mounted to said thermostat-operated lever, and a spring interposed between said member and lever.

2. The combination of a thermostat, a lever operated thereby, a valve, a member engaging said valve and pivotally mounted to said thermostat-operated lever, a spring interposed between said member and lever, and means to regulate the tension of said spring.

3. The combination of a thermostat, a lever operated thereby, a valve, a member engaging said valve and pivotally mounted to said thermostat-operated lever, a spring interposed between said member and lever, and means to limit the movement of said pivoted member.

4. The combination of a thermostat, a lever operated thereby, a valve, a member engaging said valve and pivotally mounted to said thermostat-operated lever, a spring interposed between said member and lever, means to regulate the tension of said spring, and means to limit the movement of said member.

In testimony whereof, I have hereunto signed my name in the presence of two subscribing witnesses.

JOHN ELLIS.
